GARMENT HANGER

Reynolds Guyer and Richard B. Lewis, Jr., St. Paul, Minn., assignors to Waldorf Paper Products Company, St. Paul, Minn., a corporation of Minnesota

Application November 27, 1936, Serial No. 112,963

24 Claims.

(Cl. 223—37)

Our invention relates to garment hangers and particularly to garment hangers constructed of paper.

An object of the invention resides in providing a hanger of such character which will have sufficient strength and rigidity to properly support the garments hung thereon.

Another object of the invention resides in providing a garment hanger of such character suitable for supporting both coats and trousers.

A still further object of the invention resides in providing a garment hanger having a frame comprising a cross frame member and two converging frame members connected therewith and in providing means for stiffening and reinforcing the cross frame member.

Another object of the invention resides in providing a separate reinforcing member disposed adjacent the cross member for giving rigidity and strength thereto.

A feature of the invention resides in utilizing a strip of wood as the reinforcing member.

Another object of the invention resides in constructing the cross member U-shaped in cross section to provide a web and flanges extending outwardly therefrom and in disposing said reinforcing member adjacent said web.

A still further object of the invention resides in constructing said frame of a strip of paper of multiple thickness in the form of a collapsed or flattened tube, bent to form the frame U-shaped in cross section and of double thickness of material.

Another object of the invention resides in disposing the reinforcing member within the tubular frame.

An object of the invention resides in constructing the frame from a strip of material bent to form a web with two flanges issuing therefrom and further bent to form two companion flanges issuing from said first named flanges and overlying the same and flaps issuing from said companion flanges and secured together in spaced relation to said web and in further disposing said reinforcing member between said flaps and web.

Other objects of the invention reside in the novel combination and arrangement of parts and in the details of construction hereinafter illustrated and/or described.

In the drawings:

Fig. 1 is a perspective view of a garment hanger illustrating an embodiment of our invention.

Fig. 2 is a perspective view of the structure shown in Fig. 1 with the frame collapsed.

Fig. 3 is an elevational cross sectional view taken on line 3—3 of Fig. 1.

Fig. 4 is an elevational cross sectional view taken on line 4—4 of Fig. 1.

Fig. 5 is a developed view of the blank from which the frame is constructed.

Fig. 6 is a perspective view of the reinforcing member of the invention.

Fig. 7 is a view similar to Fig. 1 of a modification of the invention.

Fig. 8 is a cross sectional detail view taken on line 8—8 of Fig. 7 and drawn to a greater scale.

Fig. 9 is a longitudinal sectional view taken on line 9—9 of Fig. 7 and drawn to the same scale as Fig. 8.

Fig. 10 is a view of the blank from which the form of the invention shown in Fig. 7 is constructed.

Where garment hangers are constructed from paper and folded to give an extended area for supporting the garments placed thereon, considerable difficulty has been encountered in procuring sufficient rigidity without the use of an excess amount of paper. The present invention overcomes this difficulty as will presently become apparent.

Our invention comprises a frame A best illustrated in Fig. 1 which consists of a cross frame member 10 and two side frame members 11 and 12. The frame members 11 and 12 are hingedly connected to the frame member 10 and are adapted to be folded into substantial alignment with said cross frame member when in collapsed position, as shown in Fig. 2, or to be extended obliquely therefrom when in operative position, as illustrated in Fig. 1, in which case the said frame members converge. These frame members are longer than one-half the length of the cross frame member 10 so that said members become disposed in the form of a triangle when extended. The hanger proper further includes a hook 13 by means of which the hanger is supported and which is attached to the ends of the converging frame members 11 and 12. The several parts will now be described in detail.

The frame A is constructed from paper board, such as fiber board, cardboard, or some other suitable material and of sufficient thickness to give the desired rigidity. Due to the reinforcing member used with the invention, a considerably thinner or lighter paper stock may be used than where the same is omitted. The blank from which the frame is constructed is shown in Fig. 5 and is indicated by the reference numeral 14. This blank consists of a narrow strip of paper of uniform

width throughout, which is scored transversely at 15 and 16 to divide the same into three sections 17, 18 and 19 which form the frame members 10, 11 and 12, respectively. The section 17 of the blank is further scored along six longitudinally spaced lines 21, 22, 23, 24, 25 and 26, which extend throughout the entire length of the said section. The score lines 22, 23, 24 and 25 form in the frame member 10 two flanges 27 and 28 and a web 29 connecting the same. The score lines 21 and 26 form in the section 17 two companion flanges 31 and 32 and flaps 33 and 34 issuing therefrom. The sections 18 and 19 are similarly scored along lines 35, 36, 37, 38, 39 and 40, which extend in continuation of the score lines 21, 22, 23, 24, 25 and 26 and which extend throughout the length of the sections 18 and 19. These score lines form in the sections 18 and 19 flanges 42 and 43 connected by a web 44 and companion flanges 45 and 46 from which issue flaps 47 and 48. At the extreme ends of the sections 18 and 19 are provided score lines 51, 52 and 53 which terminate at the ends of the blank and which also extend throughout a portion of the length of the sections 18 and 19 approximately equal to one-half the length thereof.

The blank 14 is further provided with additional transverse score lines 54 and 55 which extend obliquely across the flanges 27 and 28 and the companion flanges 31 and 32 and which terminate at the score lines 15 and 16. These score lines serve a purpose to be subsequently described in detail.

The blank 14 is folded in the following manner: While the blank is still flat the same is folded along the score lines 25 and 39 and also along score lines 22 and 36 to bring the companion flanges 31 and 32 and the flanges 45 and 46 into overlying position upon the flanges 27 and 28 and the flanges 42 and 43. The score lines are so disposed that when the parts are in such position, the flaps 34 and 48 overlie the flaps 33 and 47. Before being bent the flaps 34 and 48 are coated with glue and the same caused to adhere to one another. The score lines 21 and 24 are so disposed that the companion flanges 31 and 32 are slightly wider than the flanges 27 and 28 as shown in Fig. 3, so that when the parts are brought into overlying position a space 50 is formed between the same.

Within the space 50 is disposed a reinforcing member 56 which is shown in detail in Fig. 6. This reinforcing member consists of a strip of wood of substantially the width of the web 29 and of approximately the length of the section 17 and of a thickness considerably less than its width. In assembling the device this reinforcing strip is placed between the web 29 and the flaps 33 and 34 so that when the flaps are glued together the said reinforcing strip is disposed between said web and flaps. The reinforcing strip may also be coated with glue and glued to the parts of the cross frame member 10 or the same may merely be left loose between these parts of the frame. If desired, glue may be applied to the entire inner surface of the blank 14 and the various flanges and parts thereof glued together to form a unitary composite structure of double thickness. By means of the construction employed and the method of assembling a flattened tube results, in which the reinforcing member is disposed, the flanges 33 and 28 and reinforcing member 56 being in the nature of plates which provide an extremely rigid construction. After the frame is formed the same is bent along the remaining score lines to give the frame a form U-shaped in cross section. This

is preferably accomplished by folding the sections 18 and 19 about the score lines 15 and 16, bringing the same into overlying position with respect to the section 17 and while the parts are so disposed, pressing the structure in suitable dies to bend the various flanges into proper position with respect to the webs thereof. This leaves the ends of the members 18 and 19 U-shaped. When the hanger is erected, as will presently more fully be described, the ends of the flanges of said frame members are pressed together, folding the parts along the score lines 51, 52 and 53. This forms a narrow slot between the companion flanges 45 and 46 and the portions of the flap 48 on each side of the score line 53 in which certain of the flanges of the companion member are received, as will be subsequently described in detail.

The ends of the two frame members 11 and 12 are constructed rounded as designated at 57 which is accomplished by cutting the ends of the blank 14 with scalloped edges 58, as shown in Fig. 5. At the same time, holes 59 are formed in the ends of the frame members 11 and 12 which are constructed by punching the flanges 45, 52, 43 and 46 as indicated at 61. When the parts are pressed together as described, the punched portions register with one another to form the holes 59 referred to.

The hook 13 is constructed from wire and is formed as illustrated in Figs. 1 and 3. This hook has a hook portion 62 which opens outwardly and which is adapted to be hooked about a pole, rod or any other suitable support. The hook portion 62 has a shank 63 depending therefrom which terminates in a clip 64. Clip 64 consists of two spaced substantially parallel reaches 65 and 66 which are connected together by means of a connecting portion 67. The clip 64 serves to secure the ends of the frame members 11 and 12 together and the two reaches 65 and 66 are spaced apart a distance slightly greater than the combined thickness of the composite assembled structure.

The manner of using the invention is as follows: In the manufacture of the hangers the frames are arranged with the frame members nesting as shown in Fig. 2, and the hooks 13 are kept separate. When the hanger is desired for use the two frame members 11 and 12 thereof are first raised until the ends of said frame members clear each other. The flange structures of the ends of the frame members 11 and 12 are then pressed together. The flanges 45 and 42 of frame member 12 are then inserted between the flanges 45 and 46 of the frame member 11. This causes the flanges 43 and 46 of frame member 11 to lie between the flange 45 and flange 46 of frame member 12. The parts are then arranged so that the holes 59 of the respective flanges register with one another. The hook portion 62 of hook 13 is next inserted through the various holes 59 and the shank 63 thereof threaded through these holes until the ends of the flanges are received within the clip 64. When the parts are so disposed the various flanges are drawn together and rigidly held in juxtaposition. The connecting portion 67 of clip 64 in such case passes through all of the holes 59. The hanger is now ready for use.

In order to cause the flanges of the cross frame member 10 to extend angularly from the web of the same throughout the entire length of the cross member the score lines 54 and 55 are employed which cause the parts to fold as illus-

trated in Figs. 1 and 3. This makes the cross frame member 10 narrower than the frame members 11 and 12 at the hinge connections between the same. Such construction gives greater strength to the cross frame member and at the same time causes the converging frame members to have a greater supporting area which serves to more efficiently support the coat through the shoulders thereof. It will be noted that the frame folds jointly along the score lines 54 and 55 and the score lines 15 and 16 to provide triangular pieces 73 in the form of gussets which hold the parts in proper relation. These pieces also facilitate the collapsing of the frame and serve to stiffen and reinforce the various frame members.

In Figs. 7 to 10 we have shown a modification of the invention in which a rectangular shaped cross frame member is employed instead of a U-shaped member as shown in Fig. 1. In this form of the invention the two side frame members are constructed identical with those shown in Fig. 1 and the description thereof will not be repeated and the same reference numerals will be used to indicate corresponding parts.

The cross frame member of this form of the invention is indicated at 110 and is constructed in the following manner: The blank from which this form of the invention is constructed is indicated by the reference numeral 114. Said blank, at its center, is constructed with two longitudinally extending score lines 123 and 124 which lie in continuation of the score lines 37 and 38. Adjacent these two score lines are two other score lines 122 and 125 which are closely positioned to the score lines 123 and 124. The blank is sheared along two longitudinal lines 121 and 126 which lie in continuation of the score lines 35 and 40 and also along transverse lines 115 and 116 which are disposed at the locality of the score lines 15 and 16 and which extend between the score lines 35 and 36 and between the score lines 38 and 40. By means of this construction a web 129, two adjoining flanges 127 and 128, and flaps 133 and 134 connected therewith are formed in the center portion of the blank leaving strips 71 at the lateral edges of the blank which lie in continuation of the flaps 47 and 48 of the ends of the blank.

The manner of assembling the device is as follows: The blank 114 is covered throughout its entire exposed area with glue or some other suitable adhesive. The same is then folded along score lines 39 to bring the overlying parts into juxtaposition which are then secured together. This causes the companion flanges 46 to overlie the flanges 43; the flaps 48 to overlie the webs 44 and the strip 71 to overlie the web 129. Additional glue is then placed upon the exposed surface of the strip 71 and the reinforcing member 56 placed upon the same. The blank is next folded along score lines 36 causing the companion flanges 45 to overlie the flanges 42, the flaps 47 to overlie the flaps 48 and the strip 71 to overlie the reinforcing member 56. These parts are then pressed together. Thereafter the severed structure is folded around the reinforcing strip by bringing the flanges 127 and 128 along the edges of the reinforcing member 56 and by bringing the flap 133 upon the strip 71 and the flap 134 upon the strip 133. The arrangement of the parts of the hanger is illustrated in detail in Fig. 8. After the parts have been folded, as described, the same are pressed in suitable dies with the frame members 11 and 12 nesting and with the

frame member 110 disposed within the bight formed between the flanges and webs of one of said first named frame members.

The other parts of the form of the invention shown in Fig. 7 are identical with those previously described and the method of assembly and use is the same as that previously referred to. With the form of the invention shown in Fig. 7 a narrower pants support is provided and a neater looking article results. However, the function and operation remain substantially the same as with the first described form of the invention.

Our invention is highly efficient in that an extremely rigid and substantial construction is provided utilizing a minimum amount of paper. Our invention may be constructed at an extremely small expense. By the use of the reinforcing member disposed as shown, a small strip of inexpensive material may be used which greatly stiffens the cross frame member which receives the greater bending strain. By constructing the hanger as shown, no sharp edges of the paper are formed so that shedding of paper on the garment at such edges is prevented and injury to the garment eliminated. By the absence of sharp edges no creases are formed in the garment when the garment is allowed to hang on the hanger for an appreciable length of time.

Subject matter disclosed but not claimed in this application is claimed in the application of Reynolds Guyer, Serial No. 77,320, filed May 1, 1936.

Changes in the specific form of our invention, as herein disclosed, may be made within the scope of what is claimed without departing from the spirit of our invention.

Having described our invention, what we claim as new and desire to protect by Letters Patent is:

1. A garment hanger comprising a frame constructed of a strip of paper bent intermediate its ends to provide a one piece cross member and two converging members extending from the cross member and overlapping at their free ends, a hook attached to the free ends of said converging members for securing said ends together to form a support for said frame, an auxiliary reinforcing member constructed from a separate piece of material and extending throughout the length of said cross member and free from said converging members, and means for holding said reinforcing member in reinforcing relation with respect to said cross member.

2. A garment hanger comprising a frame constructed of paper and having a cross member and converging members connected together and to said cross member, supporting means attached to said converging members, said cross member being constructed from a sheet of paper bent U-shaped in form to provide a web and flanges issuing outwardly therefrom, and a reinforcing member disposed along the web of said cross member.

3. A garment hanger comprising a frame having a cross member and converging members connected together and to said cross member, supporting means attached to said converging members, said cross member being constructed from a sheet of paper bent to provide a web, flanges issuing from said web, companion flanges issuing from said first named flanges and overlying the same and flaps issuing from said companion flanges and secured together, said flaps being spaced from said web, and a reinforcing member disposed between said flaps and web.

4. A garment hanger comprising a frame having a cross member and converging members connected together and to said cross member, supporting means attached to said converging members, said cross member being constructed from a sheet of paper bent to provide a web, flanges issuing from said web, companion flanges issuing from said first named flanges and overlying the same and flaps issuing from said companion flanges and secured together, said flaps being spaced from said web, and a wood strip disposed between said flaps and web.
5. A garment hanger comprising a frame having a cross member and converging members integral therewith and connected together at their points of convergence, supporting means connected to said converging members, said frame being constructed of a strip of paper of multiple thickness in the form of a collapsed tube bent at portions of the same to give to the frame members at such portions a form U-shaped in cross section and of double thickness.
6. A garment hanger comprising a frame having a cross member and converging members integral therewith and connected together at their points of convergence, supporting means connected to said converging members, said frame being constructed of a strip of paper of multiple thickness in the form of a collapsed tube bent throughout the length thereof to give the frame members a form U-shaped in cross section and of double thickness.
7. A garment hanger comprising a frame having a cross member and converging members connected together and to said cross member, supporting means attached to said converging members, said cross member being constructed from a sheet of paper bent to provide a web, flanges issuing from said web, companion flanges issuing from said first named flanges and overlying the same and flaps issuing from said companion flanges and overlying one another, said flaps being secured together, said flaps being spaced from said web, and a reinforcing member disposed between said flaps and web.
8. A garment hanger comprising a unitary frame having a cross member and converging members connected together and to said cross member, supporting means attached to said converging members, said frame being constructed with upper and lower layers of material spaced from one another along the cross frame member, and a reinforcing member disposed along said cross member and between said layers of material.
9. A garment hanger comprising a frame constructed of paper and having a cross member and converging members connected together and to said cross member, supporting means attached to said converging members, said cross member being constructed from a sheet of paper bent to provide a web, flanges issuing from said web, overlying the same and a reinforcing member extending along said web.
10. A garment hanger comprising a frame having a cross member and converging members integral therewith and connected together at their points of convergence, supporting means connected to said converging members, said frame being constructed of paper bent at the cross frame member thereof to give the same a form U-shaped in cross section providing flanges and a web connecting the same, and a reinforcing member extending along the web of said cross frame member.
11. A garment hanger comprising a frame having a cross member and converging members integral therewith and connected together at their points of convergence, supporting means connected to said converging members, said frame being constructed of a strip of paper of multiple thickness in the form of a collapsed tube bent at the cross frame member thereof to give the same a form U-shaped in cross section and of double thickness and providing flanges and a web connecting the same and a reinforcing member extending along the web of said cross frame member.
12. A garment hanger comprising a frame having a cross member and converging members integral therewith and connected together at their points of convergence, supporting means connected to said converging members, said frame being constructed of a collapsed tube of paper bent at portions of the same to give to the frame members at such portions a form arched in a cross section and of double thickness.
13. A garment hanger comprising a frame having a cross member and converging members connected together and to said cross member, supporting means attached to said converging members, said cross member being constructed from a sheet of paper bent to provide a web, a reinforcing member extending along said web, said cross member being further constructed to provide flanges extending along said reinforcing member and flaps issuing from said flanges and overlying said reinforcing member, said flaps being secured to one another.
14. A garment hanger comprising a frame having a cross member and converging members connected together and to said cross member, supporting means attached to said converging members, said cross member being constructed from a sheet of paper slit intermediate its edges and along the cross frame member to provide an intermediate portion and strips extending along said intermediate portion, a reinforcing member extending along the intermediate portion of the sheet, said intermediate portion being constructed to form a tube enveloping said reinforcing member, said strips reinforcing said tube.
15. A garment hanger comprising a frame having a cross member and converging members connected together and to said cross member, supporting means attached to said converging members, said cross member being constructed from a sheet of paper slit intermediate its edges and along the cross frame member to provide an intermediate portion and strips extending along said intermediate portion, a rectangular reinforcing member extending along the intermediate portion of the sheet, said intermediate portion being folded about said reinforcing member and the edges thereof overlapping and being secured together to form a tube enveloping said reinforcing member, said strips extending along said tube.
16. A garment hanger comprising a frame having a cross member and converging members connected together and to said cross member, supporting means attached to said converging members, said cross member being constructed from a sheet of paper slit intermediate its edges and along the cross frame member to provide an intermediate portion and strips extending along said intermediate portion, a reinforcing member extending along the intermediate portion of the sheet, said intermediate portion being constructed to form a tube enveloping said reinforcing member.

- ing member, said strips being received within said tube.
17. A garment hanger comprising a frame having a cross member and converging members connected together and to said cross member, said cross member consisting of two plates connected to the converging members and a reinforcing plate disposed between said first named plates and secured thereto throughout the overlying surfaces thereof.
18. A garment hanger comprising a frame having a cross member and converging members connected together and to said cross member, said cross member consisting of two plates integral with the converging members and a reinforcing plate disposed between said first named plates and secured thereto throughout the overlying surfaces thereof.
19. The method of forming garment hangers which consists in placing a reinforcing member upon an elongated strip of material, in folding the elongated strip of material longitudinally along spaced lines, to bring the marginal portions of the strip in overlying position upon the intermediate portion of the strip and upon said reinforcing member, in securing the folded portions and reinforcing member together and in subsequently folding the folded structure transversely at spaced intervals to form end parts overlying the intermediate parts.
20. The method of forming garment hangers which consists in placing a reinforcing member upon an elongated strip of material, in folding the elongated strip of material longitudinally along spaced lines, to bring the marginal portions of the strip in overlying position upon the intermediate portion of the strip and upon said reinforcing member, in securing the folded portions and reinforcing member together, in there-
after folding the folded structure transversely at spaced intervals to form end parts overlying the intermediate parts and in subsequently folding the folded structure jointly longitudinally to give to all of the parts an arched cross section.
21. The method of forming garment hangers which consists in folding an elongated strip of material longitudinally along spaced lines to bring the marginal portions of the strip into overlying position with respect to the intermediate portion of the strip and securing the same to-
gether and in subsequently folding the folded structure transversely at spaced intervals to form end parts overlying the intermediate parts.
22. The method of forming garment hangers which consists in folding an elongated strip of material longitudinally along spaced lines to bring the marginal portions of the strip into overlying position with respect to the intermediate portion of the strip and securing the same together, in thereafter folding the folded structure transversely at spaced intervals to form end parts overlying the intermediate parts and in subsequently bending the folded structure jointly longitudinally to give all of the parts an arched cross section.
23. A garment hanger comprising a frame constructed of a relatively flat strip of paper bent intermediate its ends to provide a one piece cross member and two converging members extending from the cross member and overlapping at their free ends, said converging and cross members being channel-shaped in cross section, a hook attached to the free ends of said converging members for securing said ends together to form a support for said frame, an auxiliary reinforcing member constructed from a separate piece of material and extending throughout the length of said cross member, and means for holding said reinforcing member in reinforcing relation with respect to said cross member.
24. A garment hanger comprising a frame constructed of a relatively flat strip of paper bent intermediate its ends to provide a one piece cross member and two converging members extending from the cross member and overlapping at their free ends, said converging and cross members being channel-shaped in cross section, a hook attached to the free ends of said converging members for securing said ends together to form a support for said frame, an auxiliary reinforcing member constructed from a separate piece of material and extending along said cross member, said reinforcing member being confined within said channel-shaped cross member, and means for holding said reinforcing member in reinforcing relation with respect to said cross member.
